UNITED STATES PATENT OFFICE.

ANTONIO DELGRANDE, OF PETERSBURG, VIRGINIA, ASSIGNOR OF TWO-THIRDS TO ROBERT H. SEABURY AND NICHOLAS DELGRANDE, OF PETERSBURG, VIRGINIA.

FIRE-CRACKER.

SPECIFICATION forming part of Letters Patent No. 692,769, dated February 4, 1902.

Application filed November 11, 1901. Serial No. 81,923. (No model.)

To all whom it may concern:

Be it known that I, ANTONIO DELGRANDE, a citizen of the United States, residing at Petersburg, in the county of Dinwiddie and State of Virginia, have invented a new and useful Fire-Cracker, of which the following is a specification.

This invention relates to fire-crackers, and more particularly to that class known as "cannon-crackers."

The object of the invention is in a simple, thoroughly efficient, and practical manner to eliminate the element of danger attending the use of fire-crackers of the above description, and which has caused their use to be prohibited in certain sections, and at the same time to impart added novelty to the cracker when fired.

With these and other objects in view, as will appear as the nature of the invention is better understood, the same consists, generally stated, in combining with the fire-cracker an element capable of giving a visual signal to indicate that the fuse is properly ignited and is burning or that the fuse is extinguished or of elements capable of giving a combined visual and audible signal for the same purpose.

In the accompanying drawings, forming a part of this specification, and in which like numerals of reference indicate corresponding parts, there are illustrated two forms of embodiment of the invention capable of carrying the same into practical operation, it being understood that the elements therein exhibited may be varied or changed as to shape, proportion, and exact manner of assemblage without departing from the scope of the invention, and in these drawings—

Figure 1 is a view in sectional elevation, exhibiting a fire-cracker constructed to give a visual signal to indicate that the cracker is ignited and that an explosion will follow. Fig. 2 is a similar view exhibiting a fire-cracker constructed to give first a visual and then an audible signal for the purpose above stated.

Referring to the drawings and to Fig. 1 thereof, 1 designates the shell or body of the

cracker, the same to be constructed of any material suited to the purpose and incloses a charge of powder 2, the butt-end of the shell being closed by a plug 3, of cork or any other substance suited to the purpose, and the firing end being closed by a plug 4, preferably of fire-clay and located some distance within the said end. Housed within the shell above the plug 4 is a body of illuminating material 5, which is adapted upon ignition to burn with a distinctive color—such as red, blue, green, or the like—the said material being any one of the chemical compounds or other substances employed for the purpose in ordinary pyrotechnic devices, and therefore needs no detailed description. The material may be tamped or otherwise placed within the shell and may be spaced from the plug 4, as shown, or may rest thereon. To shield the material from accidental ignition and also to hold the igniting-fuse 6 within the shell, the wrapper 7 projects beyond the firing end thereof, as shown at 8, and is twisted around the fuse and then pushed into the said end of the shell. As shown in the said figure, the fuse 6 is disposed against one side of the shell; but it is to be understood that it may be centrally disposed thereof, if preferred.

Embedded in the compound 5 is one end of a fuse 9, which extends through the plug 4 and into the charge of powder, and by this disposition of the parts the fuse 9 will not be ignited until the illuminating material is burned out, thereby giving the user of the cracker ample time to dispose of the cracker after the fuse 6 is ignited and before the fire reaches the fuse 9.

In the use of the cracker constructed as above described fire is applied to the fuse 6 and burns down and ignites the illuminating material, which burns and gives a brilliant light, affording thereby a visual signal to show that the cracker is properly ignited. When the material has all been consumed, the fuse 9 is ignited and burns down and ignites the charge of powder, whereupon the explosion takes place.

In the form of cracker shown in Fig. 2 the

shell is constructed in the same manner as that shown in Fig. 1, and the charge of powder is held in at the butt-end of the shell by the plug 3, as described. The firing end of the 5 cracker contains a charge of illuminating material 10, which is held within a tube 11, of paper or any other suitable material, and embedded in the said material is an igniting-fuse 6, the charge of illuminating material 10 being shielded by the wrapper in the same manner as that described in connection with Fig. 1.

Projecting through the fire-clay plug 4 is a tube 12 containing picrate of potash, a substance which upon burning emits a shrill 15 whistling sound distinctive to that class of pyrotechnics known as "whistling bombs," the upper and lower ends of the said tube being preferably provided with a plug of 20 powder 13, by which to insure proper ignition of the whistling substance and of the charge of powder.

In the use of the cracker constructed as above described fire is applied to the fuse 6 25 and burns down and ignites the illuminating material, which burns and gives a brilliant light, affording thereby a visual signal to show that the cracker is properly ignited. When all the illuminating material is consumed, the picrate of potash is ignited and 30 burns, giving forth a shrill whistling sound, which serves as an audible signal to show that the cracker is properly ignited and that an explosion will soon follow, and when all 35 the picrate of potash is consumed the fire therefrom ignites the powder, whereupon the explosion of the cracker takes place. It is to be understood that the signals of this latter form of cracker may be transposed—that 40 is to say, the tube containing the whistling compound may be placed at the firing end of the cracker and the illuminating material beneath the same, and as this will be readily understood detailed illustration thereof is 45 deemed unnecessary.

It will be seen from the foregoing description that in addition to imparting added novelty to the fire-cracker by the provision of colored fire or of the colored fire and the whistling compound the element of danger attending the use of these crackers is positively 50 eliminated, so that the objections strenuously

urged in many localities against the use of cau-
non fire-crackers is entirely obviated.

Having thus fully described my invention, 55 what I claim as new, and desire to secure by Letters Patent, is—

1. A fire-cracker provided with means for giving a visual signal, of a pronounced character, and other than that produced from the 60 smoke and flame resulting from combustion, in advance of the explosion of the cracker.

2. A fire-cracker containing a material adapted upon ignition to give a visual signal of a pronounced character, said material 65 constituting a means of igniting a charge of powder.

3. A fire-cracker provided with means for giving consecutively a visual and an audible signal in advance of the explosion of the 70 cracker.

4. The combination with a fire-cracker, of a holder containing a "whistling compound," and a charge of illuminating material.

5. A fire-cracker containing a charge of 75 illuminating material adapted upon ignition to give a visual signal in advance of the explosion of the cracker.

6. A fire-cracker containing a charge of powder, a charge of illuminating material 80 separated therefrom by a non-combustible substance, and a fuse connecting the illuminating material and the powder.

7. A fire-cracker containing a charge of powder, a charge of illuminating material 85 separated therefrom by a non-combustible substance, and a holder embedded in the said substance and containing a whistling compound.

8. A fire-cracker containing a charge of 90 powder, a charge of illuminating material separated therefrom by a non-combustible substance, and a holder embedded in the said substance and in the powder and containing a whistling compound, the illuminating material operating to ignite the said compound, 95 and the latter to ignite the powder.

In testimony that I claim the foregoing as my own I have hereto affixed my signature in the presence of two witnesses.

ANTONIO DELGRANDE.
